UNITED STATES PATENT OFFICE

107,345

DESIGN FOR AN AUTOMOBILE DIRECTION SIGNAL

William M. Wicker, Sr., Carlyle, Ill.

Application May 1, 1937, Serial No. 69,119

Term of patent 3½ years

To all whom it may concern:

Be it known that I, William M. Wicker, Sr., a citizen of the United States, residing at Carlyle, in the county of Clinton and State of Illinois, have invented a new, original, and ornamental Design for an Automobile Direction Signal, of which the following is a specification, reference being had to the accompanying drawing, forming part thereof.

Figure 1 is a view in front elevation of an automobile direction signal, showing my new design.

Figure 2 is a top plan view thereof.

Figure 3 is a side elevational view.

I claim:—

The ornamental design for an automobile direction signal, as shown.

WILLIAM M. WICKER, SR.
